UNITED STATES PATENT OFFICE.

CLAYTON FLOYD HOLMES, OF BEAUMONT, TEXAS, ASSIGNOR OF ONE-HALF TO JOSEPH FRIEBIS, OF BEAUMONT, TEXAS.

SMOKE-SEPARATOR.

1,081,116.

Specification of Letters Patent.

Patented Dec. 9, 1913.

Application filed April 12, 1913. Serial No. 760,648.

To all whom it may concern:

Be it known that I, CLAYTON F. HOLMES, a citizen of the United States, and a resident of Beaumont, in the county of Jefferson and State of Texas, have invented a new and Improved Smoke-Separator, of which the following is a full, clear, and exact description.

The object of the invention is to provide 10 a new and improved smoke separator designed for use in connection with smelter furnaces and other apparatus, and arranged to effectively prevent poisonous or obnoxious gases from passing into the atmosphere, at 15 the same time retaining and saving valuable matter contained in the smoke.

In order to accomplish the desired result use is made of a cooling flume connected at one end with a source of smoke or gases 20 and at its other end with a suction fan to draw the smoke or gases through the cooling flume, the latter being provided at its bottom with soot outlets leading to soot-receiving receptacles, cooling coils arranged 25 within the cooling flume and connected with a source of cooling medium, and a precipitating tank charged with water or other cooling medium and into which discharges the said suction fan, said precipitating tank 30 having a jet pipe for supplying the cooling medium to the tank.

A practical embodiment of the invention is represented in the accompanying drawings forming a part of this specification, in 35 which similar characters of reference indicate corresponding parts in all the views.

Figure 1 is a sectional plan view of the smoke separator as applied; Fig. 2 is a sectional side elevation of the same on the line 40 2—2 of Fig. 1; and Fig. 3 is an enlarged cross section of the same on the line 3—3 of Fig. 2.

A flume A leads from a smelter or other apparatus B, and this flume leads to a smoke stack C and the flume A is connected immediately prior to reaching the smoke stack C with a cooling flume D provided at its entrance end with a valve E which when open disconnects the flume A from the smoke 45 stack C and connects the flume A with the cooling flume D so that the smoke and gases from the smelter pass into and through the said cooling flume D. The forward contracted end D' of the cooling flume D connects with a suction fan F, of any approved

construction, having a discharge pipe G extending with its perforated terminal G' into a precipitating tank H filled with cold water or similar cooling medium to a distance above the perforations in the terminal G' of 60 the pipe G so that the smoke and gases pass into and through the water contained in the precipitating tank H.

Within the cooling flume D are arranged a series of connected cooling coils I, of which 65 the last coil is connected by a pipe I' with a pump or other means for passing water or other cooling medium through the connected coils I. The first coil I of the series is connected by a pipe I² with a boiler or other apparatus for receiving the heated water in the coils I, heated by the smoke and gases during their passage through the flume D. The coils I are arranged transversely to somewhat retard the flow of the smoke and 70 gases and thus insure an intimate contact of the smoke and gases with the coils, with a view to effectively cool and condense the smoke and gases. It will be noticed that the water in the coils flows in a direction opposite 75 the flow of the smoke and gases so that the smoke and gases are gradually cooled.

The bottom of the flume D is provided with perforations D² and upwardly and rearwardly-inclined deflecting plates D³ adjacent the forward edges of the openings D², as plainly indicated in Fig. 2. Immediately below the bottom of the flume D are arranged receptacles J provided with hinged bottoms J' for opening the receptacles periodically with a view to discharge the contents thereof. It is understood that when the hot smoke and gases pass through the flume D and come in contact with the cooling coils I then a portion of the smoke and 80 gases is condensed and the solid matter drops through the opening D² into the receiving receptacle J in which the soot can accumulate to be periodically discharged therefrom, 85 as previously mentioned.

The tank H is supplied with cold water or other cooling medium by a series of annular jet pipes K connected by a pipe K' with a pump for supplying the jet pipes K with cold water or other cooling medium. An 90 overflow pipe L leads from the tank H so as to maintain the water contained therein at a predetermined level, that is, above the perforations in the terminal G' of the pipe G, so that the smoke and gases must pass 95 through the water in the tank H. The 100

through the water contained in the tank H. The bottom of the tank H is connected by a pipe N with a settling tank O, and the said pipe N is provided with a valve N' which is 5 opened from time to time to discharge the sediment accumulating in the bottom of the tank H. It is understood that the smoke and gases discharged by the action of the suction fan F by way of the pipe G into the 10 water of the tank H is deprived of solid matter which accumulates in the bottom of the tank H.

As shown in Figs. 1 and 2, the suction fan F is located in a building P while the 15 tank H is preferably located adjacent the said building. It is understood that the smoke and gases finally rising out of the open top of the tank H into the atmosphere are free of poisonous or obnoxious matter.

20 The soot received from the receptacles J and the precipitate accumulating in the tank O can be subjected to further treatment for obtaining any valuable matter that may be contained in the soot or precipitates.

25 Having thus described my invention, I claim as new and desire to secure by Letters Patent:

1. A smoke separator for smelter furnaces and like apparatus, comprising a cooling flume connected at one end with the apparatus, a suction fan connected with the other end of the said cooling flume, a series of connected and vertically extending cooling coils arranged transversely within the said flume to retard the passage of the smoke and gases through the flume and to cool the said smoke and gases, and a precipitating tank charged with a cooling medium and into which discharges the said suction fan.

40 2. A smoke separator for smelter furnaces and like apparatus, comprising a cooling flume connected at one end with the apparatus, and having openings in its bottom, a suction fan connected with the other end of 45 the said cooling flume, a series of connected and vertically extending cooling coils arranged transversely within the said flume to retard the passage of the smoke and gases through the flume to cool the said smoke and 50 gases, means for delivering water to the coil adjacent to the outlet end of the flume, a

precipitating tank charged with a cooling medium and into which discharges the said suction fan, the tank being open at the top, and means for delivering a cooling medium 55 in jets in the open top of the said precipitating tank.

3. A smoke separator for smelter furnaces and like apparatus, comprising a flume leading from the apparatus to a stack, a cooling flume connected at one end with the flume of the apparatus and provided at its entrance end with a valve, which when open, closes communication between the stack and apparatus, a suction fan connected with the other 60 end of the said cooling flume, a series of connected and vertically extending cooling coils arranged transversely within the said flume to retard the passage of the smoke and gases through the flume and to cool the said smoke 65 and gases, means for delivering water to the coil adjacent to the outlet end of the flume; a precipitating tank charged with a cooling medium and into which discharges the said suction fan, a settling tank and a valved connection between the bottom of the said precipitating tank and the said settling tank.

4. A smoke separator for smelter furnaces and like apparatus, comprising a cooling flume connected at one end with the apparatus and provided in its bottom with openings and transversely-extending inclined deflecting plates, soot-receiving receptacles arranged under the said flumes and into which lead the said openings, vertically extending 80 and connected cooling coils arranged transversely within the said flume and connected at one end with a source of water supply, a suction fan connected with the outer end of the said flume, a precipitating tank charged 85 with water, and a discharge pipe leading from the said suction fan and extending into the water contained in the said precipitating tank.

In testimony whereof I have signed my 95 name to this specification in the presence of two subscribing witnesses.

CLAYTON FLOYD HOLMES.
